METHOD AND MEANS FOR CONTROLLING
THE TONE OF A RADIO SETLouis F. Willging, Cincinnati, Ohio, assignor to
The Crosley Radio Corporation, Cincinnati,
Ohio, a corporation of Ohio

Application March 23, 1931, Serial No. 524,419

4 Claims. (Cl. 250—20)

My invention is addressed to means for effecting so-called tone control in radio sets; but it is an object of my invention to provide means and a method for tone control which goes beyond the mere relative suppression of undesired frequencies, and accentuates the desired frequency range.

It is an object of my invention to provide in a tone control means and a method, when, for example, the treble range is desired, not only to suppress the lower frequencies, but to reinforce and build up the volume of the higher frequencies.

Conversely, it is my object when stronger bass values are desired, to provide a means and method not only to suppress the higher frequencies, but also build up, reinforce, and strengthen the lower frequencies.

Consequently, it is my object to achieve in a tone control, adequate and full range variation of tone, so called, without substantial change in volume.

It is a further object of my invention to provide a tone control which is continuously variable from extreme treble to extreme bass.

These and the more specific objects of my invention which will be set forth hereinafter, or will be apparent to one skilled in the art upon reading these specifications, I accomplish by that certain construction and arrangement of parts of which I shall now describe a preferred embodiment, reference being had to the drawing in which I have shown only so much of a radio circuit as is necessary to the comprehension of my invention.

My method is applied to the audio frequency portion of a radio receiving system, but is not restricted to any particular type of set or circuit.

In the practice of my invention I raise the tone, so called, by accentuating the higher frequencies. This is accomplished by regeneration at the higher frequency, involving the feeding back of energy in the right phase and magnitude from the plate of an audio frequency tube to the plate of a preceding tube. I also lower the tone of a radio set by suppressing the high audio frequencies and accentuating the low frequencies by introducing parallel resonance in the primary of an audio frequency transformer. My means are continuously variable from one extreme to the other.

Thus in the treble position I achieve actually increased high frequency response by proper phasing so as to produce audio regeneration at high frequencies. By shifting my tone control

from the treble position, resistance is introduced into the feed back circuit in such a way as ultimately to eliminate the said regeneration. During the shift however, resistance is progressively taken out of a parallel resonance circuit comprising the primary of an audio frequency transformer and a condenser of desired capacity so that the low frequencies are augmented simultaneously with the attenuation of the high frequencies.

This is accomplished by inexpensive mechanism which comprises only a potentiometer and two fixed capacities; and with this explanation my drawing will be clear. I have shown at 1 an audio frequency tube, the plate 2 of which feeds the primary 3 of an audio frequency transformer indicated generally at 4. The secondary 5 of this transformer feeds the grid 6 of a succeeding audio frequency tube 7. The plate 8 of this tube is connected through a fixed capacity 9, to one end of the resistance element of a potentiometer 10. The plate 2 of the tube 1 is connected through the fixed capacity 11 to the arm or variable contact point 12 of the potentiometer 10. The other end of the resistance element of the potentiometer is connected by a lead 13 to the grounded side of the primary of the transformer 4.

When the contact arm 12 is in the extreme left hand position in the figure, the condenser 11 will in effect be connected in parallel across the primary of the transformer 4 resonating it at some low frequency range, thus accentuating the low notes. As the arm 12 is moved toward the right in the figure, more and more resistance is inserted into this resonant circuit. At the same time however, resistance is removed progressively from a feed back circuit connection between the plate 8 of tube 7 and the primary 3 of transformer 4. This feed back connection comprises in series the capacities 9 and 11, and it will be noted that the connection is such that energy is fed back in proper phase relationship for regeneration.

The values of capacities 9 and 11 and of the resistance of the potentiometer 10 may be readily selected for a desired tone control with reference to the other constants of the set. Tone control is, as explained, achieved by the operator merely by movement of the potentiometer arm. The change in response is gradual, and any compromise may be reached between the two extremes. Of course the regenerative circuit may be caused to respond to low frequencies and the resonance circuit to high frequencies, if desired.

Having thus described my invention, what I claim as new and desire to secure by Letters Patent, is:—

- 5 1. In a radio set an audio frequency tube and circuit means connecting the plate of said tube with the primary of a preceding audio frequency transformer in proper phase for regeneration, a circuit comprising a condenser paralleled across the primary of an audio frequency transformer preceding said tube, and controllable means for introducing resistance in inverse proportion into the two circuits.
- 10 2. In a radio set a tone control comprising an audio frequency tube, a connection comprising a capacity between said tube and the primary of a preceding audio frequency transformer, a connection comprising a capacity paralleled across said primary, and means for varying the response effects of the resonance and regeneration circuits formed by said connections, said means comprising a potentiometer common to both circuits.
- 15 3. In a radio set a tone control comprising in combination with an audio tube, and a preceding

audio transformer, a potentiometer, a lead comprising a capacity connecting one end of the resistance element of said potentiometer to the plate of said tube, a lead connecting the other end of said resistance element to the grounded side of the primary of said transformer, and a connection including a capacity between the variable arm of said potentiometer and the ungrounded side of said transformer.

4. In a radio set a tone control comprising in combination with an audio frequency tube and a preceding audio frequency transformer, a potentiometer, a connection including a fixed capacity between said potentiometer and the plate of said tube, a connection including a fixed capacity between said potentiometer and the primary of said transformer, said connections effecting a feedback circuit for energy in proper phase for regeneration, said circuit including both said capacities, and a connection between said potentiometer and said primary whereby one of said capacities may be shunted thereacross.

LOUIS F. WILLGING.
